VISIBLE CARD INDEX

Filed March 25, 1927

UNITED STATES PATENT OFFICE

LUIGI LOMBARDINI, OF TURIN, ITALY

VISIBLE-CARD INDEX

Application filed March 25, 1927, Serial No. 178,359, and in Italy April 12, 1926.

The invention relates to improvements in card indexes and particularly to that class in which the cards are held on a support so as to overlap one another.

5 The object of the invention is to provide index cards so that they can be readily applied to and removed from the support. The invention consists of a card having front and rear portions provided with a central passage 10 between them, one of the portions having an opening and tongues to facilitate the entrance of a support into said opening and retain the support in said opening and the other portion having a tongue adapted to enter the passage 15 sage of a previously applied card, so that the cards can be applied to the support one overlapping the other.

In the drawing:

20 Figure 1 is a detail view of a part of a card, Figure 2 is a side view of both parts of the card together with a portion of a support for the card with which it is engaged,

Figure 3 is a transverse section of Figure 2, and

25 Figures 4 and 5 are an elevation and a cross section respectively of a modified form of card.

Fig. 6 is a view of two of the cards of the first form in nested relation.

30 Like reference characters designate corresponding parts in all of the views.

The card is composed of two parts 11 and 11'. The part 11 is provided with the central tongue 12 projecting from its upper edge and 35 with a flap at each side of the tongue, said flaps forming two members 13 and 13'. The other part 11' of the card consists of a central portion formed with a horizontal slot 20 spaced from the top edge a distance equal to 40 the overlap of the cards, from one end of which slot the oblique curved slot 20' extends out through the lower end of said part and forms the downwardly projecting tongues 17 and 18. The part 11' of the card has at its

45 upper end band-like members 15 and 16, the ends of which extend between the members 13 and 13' of the first part and are secured therebetween by staples passed through the several parts. Any other suitable means may be 50 employed for securing the said parts together.

By thus constructing the tongues, a support can be readily inserted in the slot 20 and when so inserted a portion of each tongue will overlie the support and thus retain the support in the slot and the card on the support.

55

As shown in the drawing the support is a bar or rod 1, but a tape, cord or other flexible support may be employed. To apply the card to the bar 1 a card is brought into engagement with the bar and said bar or card is

60

moved laterally to cause the bar to enter the oblique slot 20' and pass under one of the tongues 17 or 18 and enter the slot 20, and then by a reverse movement of the bar or

65

card, the bar will pass under the other tongue and the card will be held on said bar. To remove the card the bar or card is manipulated to cause the bar to pass out through the slot 20'. When another card is to be applied

70

to the bar 1, the card is applied to the bar below the first card in the same manner as the first card and then it is slid upward on the bar under the tongues 17 and 18 of the first card, when its tongue 12 will pass into the passage between the parts of the cards.

75

It will thus be seen that the cards can be readily and quickly applied and that when a number of cards are applied they will be nested or overlap one another. In the modification of Figures 4 and 5, the construction

80

of the card is similar to that shown in the other figures, except that the parts of the card are secured together a little differently. In these views the members 13^a are provided

85

with a slot 22 of a length slightly greater than the width of the band-like members 15 and 16. Thus, it will be seen that the members 13^a provide tabs 23 and 24. The band-like members 15 and 16 of the parts 11' are disposed within the slot 22 so as to position the tabs 23 and 24 upon alternate sides of the bands 15 and 16. The bands 15 and 16 may be secured to the tabs 23 and 24 by staples 25.

90

What I claim is:

1. A visible card index comprising a guide 95 and a card formed of two interconnected parts and adapted to be inserted on the guide with one part beneath the guide and the other part partly underlying and partly overlying said guide.

100

2. In a card index, a card formed of two parts secured together to form a central passage between them, one part having a tongue at its upper edge adapted to enter the passage of an adjacent card and the other part having two tongues, and an opening adapted to receive a support and providing portions adapted to overlie the support and hold the support in the opening.
- 10 3. In a card index, a card formed of two parts secured together to form a passage between them, one part being provided with a tongue at its upper edge, adapted to enter the passage of the adjacent card, the other part having a horizontal slot spaced from its upper edge and a curved slot leading from one end of the first-mentioned slot out through the lower end of the part and forming two tongues, and said last-named part having oppositely projecting band-like members at its upper edge.
- 15 4. In a card index provided with a guide rod, a card formed of two parts secured together to form a passage between them, one part being provided at its upper edge with a tongue adapted to be nested in the corresponding passage of an adjacent card, the other part having a horizontal slot adjacent its upper edge, said slot being of substantially the same length as the width of the guide rod, and an oblique curved slot leading from one end of said first-named slot out through the lower end of the part and forming two tongues, said tongues being defined in part by rounded edges leading from the edges of said oblique slot.
- 20
- 25
- 30
- 35

In testimony whereof, I have affixed my signature.

LUIGI LOMBARDINI.
